THROTTLE VALVE FOR STOPERS

Albert Feucht, Garfield Heights, Ohio, assignor,
by mesne assignments, to Le Roi Company,
Milwaukee, Wis., a corporation of Wisconsin

Application August 17, 1943, Serial No. 498,933

10 Claims. (Cl. 121—9)

1

This invention relates to power tools and more particularly to a fluid actuated power tool having novel valve means for controlling the operation of the tool.

An object of my invention is to provide an improved construction for a power tool of the kind having a feed cylinder and control valve therefor, and in which the control valve embodies novel means for bleeding pressure fluid to atmosphere for varying the rate of feed.

Another object of my invention is to provide an improved construction for fluid actuated tools, such as stopers or the like having feed and power cylinders and a control valve therefor, and wherein the control valve embodies novel means which is effective in certain positions of the valve for maintaining a reduced pressure of fluid supplied to the feed cylinder.

Other objects and advantages of the invention will be apparent from the following description when taken in conjunction with the accompanying sheets of drawings in which:

Fig. 1 is an elevational view of a fluid actuated tool embodying my invention;

Fig. 2 is an elevational view, on an enlarged scale, showing a portion of the tool adjacent the control valve and with portions of the valve in section;

Figs. 3, 4 and 5 are transverse sectional views taken through the control valve on section lines 3—3, 4—4, and 5—5, respectively, of Fig. 2, with the movable valve piece in the position for operation of the tool at reduced speed and with reduced feeding pressure;

Figs. 3a, 4a and 5a are similar sectional views taken respectively on lines 3—3, 4—4, and 5—5 of Fig. 2, but with the valve piece in the position for operation at full speed and with reduced feeding pressure;

Figs. 3b, 4b and 5b are similar sectional views taken respectively on lines 3—3, 4—4, and 5—5 of Fig. 2, with the valve piece in the position for operation at full speed and with full feeding pressure, and

Fig. 6 is a transverse sectional view taken through the control valve on line 5—5 of Fig. 2 and showing the valve piece in its off position with the feed cylinder vented to atmosphere.

As will become more apparent in the following detailed description, my invention is applicable to fluid actuated tools of the kind having feed and power cylinders and is particularly suitable for percussive tools such as stopers and other rock drills. In using a stoper, difficulty is frequently experienced in the "collaring" operation, that is, in getting the drill steel started in the

2

work. This step is facilitated if the drill steel can be operated at reduced speed and at the same time moved slowly up to the work by using a reduced feeding pressure. It is also desirable that, after the drill steel has been moved to the work, the stoper be capable of operation at a constant reduced speed but with an adjustable feeding pressure so as to permit the stoper to be properly held against the drill steel to obtain the cutting action necessary for collaring. When soft spots are encountered in drilling, it is also desirable to be able to run the stoper at full speed but with a reduced feeding pressure to prevent the drill steel from burying itself in the soft material. It is also necessary, of course, to be able to operate the tool at full speed and at full feeding pressure. With the valve means to be described hereinafter these conditions or requirements are fulfilled in an efficient and satisfactory manner.

In the drawings, I show a percussive tool or stoper 10 having a housing section 11 containing a power cylinder 12 for actuating the drill steel 13 and a housing section 14 containing a feed cylinder 15 for actuating an extendable thrust member 16 for feeding the tool toward the work. The housing section 11 may have a suitable handle 17 connected therewith for manipulating the tool.

For controlling the operation of the feed and power cylinders 15 and 12, the tool is provided with a control valve or throttle valve 18. This control valve comprises a housing or valve chamber 19 and a valve piece 20 which is rotatable or oscillatable therein and is provided with a handle 21 for actuating the same. The housing 19 has a fluid supply connection 22 for supplying thereto a suitable motive fluid such as compressed air.

As shown in the drawings (see Figs. 3 and 4), the valve housing 19 contains passages 23 and 24 leading respectively to the power cylinder 12 and the feed cylinder 15. The valve housing 19 also has an orifice 25 which is open to atmosphere as shown in Fig. 5. The valve piece 20 is hollow and is open at its inner end so that the pressure fluid supplied through the connection 22 enters this member. As shown in Figs. 3 and 4, the valve piece 20 has substantially radially extending power ports 26 and 27 and a substantially radially extending feed port 28. The valve piece 20 also has an arcuately extending peripheral groove 29 communicating with the feed port 28 and a plurality of circumferentially spaced axial slots or grooves, in this instance two such slots 30 and 31, which are connected with the arcuate groove 29. In addition, the valve 20 is provided

with an axial slot or groove 32 which is similar to the slots 30 and 31, but which does not communicate with the arcuate groove 29.

Figs. 3 to 5 inclusive show the valve piece 20 in the position for operation of the tool at slow speed and with reduced feeding pressure. The power port 27 is of reduced size as compared with the power port 26 and Fig. 3 shows the port 27 in communication with the passage 23 leading to the power cylinder 12 for supplying pressure fluid thereto at a rate to produce such slow speed operation. Fig. 4 shows the arcuate groove 29 as connecting the feed port 28 with the passage 24 leading to the feed cylinder 15. With the valve piece in this position, the axial slot 30 is in communication with the passage 25 leading to atmosphere (see Fig. 5) and forms a bleed connection or passage for reducing the pressure of the fluid being supplied to the feed cylinder.

It is important in the operation of the tool controlled by the valve 18 to be able to vary or adjust the reduced feeding pressure being used while the tool is being operated at reduced speed, as provided by the valve setting shown in Figs. 3 to 5 inclusive. This is especially desirable in the operation of a stoper for the above-described collaring step and is obtained by moving the valve handle 21 so that the slot 30 will cooperate with the edge of the orifice 25 and its communication with the latter passage will thereby be more or less restricted. In other words, by moving the handle 21 back and forth within a small arc extending clockwise from the handle position shown in Fig. 5, the slot 30 can be partially closed and the effectiveness of the bleed passage thereby changed to correspondingly vary the feeding pressure.

In Figs. 3a to 5a, inclusive, the valve piece 20 is shown as having been moved to the position for operating the tool at full speed but with reduced feeding pressure. Fig. 3a shows the main power port 26 in communication with the passage 23 to the power cylinder 12 and Fig. 4a shows that for this position of the valve the arcuate groove 29 is still in communication with the passage 24 leading to the feed cylinder 15. For this position of the valve, the axial slot or passage 31 is in communication with the atmosphere orifice 25, as shown in Fig. 5a so that the bleeding of fluid to atmosphere will reduce the pressure of the fluid being supplied to the feed cylinder 15.

Figs. 3b to 5b, inclusive, show the valve piece 20 in its final or full on position in which the tool is operated at full speed or power and with full feeding pressure. With the valve in this position, the main power port 26 is in communication with the passage 23 leading to the power cylinder 12, as shown in Fig. 3b, and the arcuate groove 29 is still in communication with the passage 24 leading to the feed cylinder 15 as shown in Fig. 4b. Since full feeding pressure is desired at this time, the axial slots 30 and 31 are both out of communication with the orifice 25 and there is no bleeding of pressure fluid to atmosphere, and hence the fluid being supplied to the feed cylinder 15 is at full working pressure.

When the valve piece 20 is moved to the off position to discontinue the operation of the tool it is desirable that the pressure fluid be exhausted from the feed cylinder 15 so as to permit the thrust member 16 to be retracted. The axial slot 32 is provided in the valve piece 20 for the purpose of exhausting the pressure fluid from the feed cylinder 15 and is so located that when the

valve is moved to its off position, as shown in Fig. 6, this slot will connect the passage 24 with the atmosphere orifice 25 for relieving the pressure in the feed cylinder.

5 The valve piece 20 can be releasably retained in the different positions to which it is movable, by employing suitable retaining means such as a detent (not shown) which is engageable in slots or recesses 34 provided in the valve at circumferentially spaced points.

15 From the foregoing description and the accompanying drawings it will now be readily apparent that I have provided an improved fluid actuated tool having a novel control valve or throttle valve which will permit operation of the tool at different speeds and will enable the operator to use either full pressure or a reduced pressure for feeding the drill toward the work. It will be seen further that the novel control valve 20 which I have provided permits fluid to be bled to atmosphere in obtaining the reduced pressure for the fluid being supplied to the feed cylinder.

25 While I have illustrated and described my improved power tool and the control valve therefor in considerable detail, it will be understood of course that I do not wish to be correspondingly limited, but regard my invention as including all changes and modifications coming within the spirit of the invention and the scope of the appended claims.

30 Having thus described my invention, I claim:

1. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece operable in said housing having ports for connection simultaneously with said motor fluid passage and said feed passage, the interior of 35 said hollow valve piece being in communication with said inlet whenever either of said ports is in operative position, and said valve also having a bleed passage adapted, when the valve piece is in position to connect said feed passage with said 40 inlet, for connecting said feed passage with said orifice independently of said motor fluid passage.

2. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece operable in said housing having ports for connection simultaneously with said motor fluid passage and said feed passage, the interior of 45 said hollow valve piece being in communication with said inlet whenever either of said ports is in operative position, and said valve also having a bleed passage adapted, when the valve piece is in position to connect both of said passages 50 with said inlet, for connecting said feed passage with said orifice independently of said motor fluid passage.

3. In a valve for distributing pressure fluid to the motor and feed cylinder of a stoper, a valve 55 housing having an inlet for pressure fluid, a passage for motor fluid, a passage for feed fluid and an orifice leading to atmosphere, a hollow valve piece operable in said housing having ports for connection with said motor fluid passage and said feed passage, the interior of said hollow valve piece being in communication with said inlet whenever either of said ports is in operative position, and said valve also having a bleed passage adapted, when the valve piece is in position 60 to connect said feed passage with said inlet, for

connecting said feed passage with said orifice independently of said motor fluid passage, the degree of opening of said bleed passage being variable while the motor fluid port remains in communication with the motor fluid passage.

4. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece operable in said housing having ports for connection with said motor fluid passage and said feed passage, the interior of said hollow valve piece being in communication with said inlet whenever either of said ports is in operative position, and said valve also having a bleed passage adapted, when the valve piece is in position to connect said feed passage with said inlet, for connecting said feed passage with said orifice independently of said motor fluid passage, the degree of opening of said bleed passage decreasing as the motor fluid port approaches full connection with the motor fluid passage.

5. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece operable in said housing having two ports for connection successively with said motor fluid passage and a port for connection with said feed passage, the interior of said hollow valve piece being in communication with said inlet whenever either of said ports is in operative position, and said valve also having a bleed passage adapted, when the valve piece is in position to connect said feed passage with said inlet, for continuously connecting said feed passage to said orifice while one of said motor fluid ports is in communication with said motor fluid passage.

6. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece operable in said housing having two ports for connection successively with said motor fluid passage and a port for connection with said feed passage, the interior of said hollow valve piece being in communication with said inlet whenever any of said ports is in operative position, and said valve also having two bleed passages, one of which is adapted, when the valve piece is in position to connect said feed passage with said inlet, for connecting said feed passage with said orifice while one of said motor fluid ports is in communication with said motor fluid passage and the other of said bleed passages is adapted to afford the same communication while the other of said motor fluid ports is in communication with said motor fluid passage.

7. In a valve for distributing pressure fluid to the motor and feed cylinder of a stoper, a valve housing having an inlet for pressure fluid, a passage for motor fluid, a passage for feed fluid and an orifice leading to atmosphere, a valve sleeve operable in said housing having radial motor fluid and feed fluid ports adapted for connection respectively with said motor fluid and feed fluid passages, the interior of said sleeve being in communication with said inlet whenever either of said ports is in operative position, said valve sleeve also having a surface groove connected with said radial feed fluid port, said valve also having a bleed passage adapted, when the valve piece

is in position to connect said groove with said feed passage, to communicate with said orifice independently of said motor fluid passage.

8. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece in said housing shiftable to different positions having motor fluid ports movable successively into communication with said motor fluid passage, and said valve piece having feed port means including a peripheral groove movable into connection with said feed fluid passage, the interior of said hollow valve piece being in communication with said inlet whenever any of said ports is in operative position, said valve also having bleed passage means for connecting said groove with said orifice during at least part of the time that each of said motor fluid ports is in communication with said motor fluid passage.

9. In a valve for distributing pressure fluid to the motor and feed cylinder of a stoper, a valve housing having an inlet for pressure fluid, a passage for motor fluid, a passage for feed fluid and an orifice leading to atmosphere, a hollow valve piece in said housing shiftable to different positions having motor fluid ports movable successively to communicate with the said motor fluid passage, said valve piece having an arcuate surface groove adapted to maintain connection with said feed fluid passage for different positions of the valve and a radial port in communication with said groove, the interior of said hollow valve piece being in communication with said inlet whenever any of said ports is in operative position, said valve piece having spaced axially extending grooves connected with said arcuate groove movable successively to communicate with said orifice during the successive movement of said motor fluid ports in communication with said motor fluid passage.

10. In a valve for distributing pressure fluid to the motor and feed cylinder of a stoper, a valve housing having an inlet for pressure fluid, a passage for motor fluid and a passage for feed fluid, a valve piece in said housing having a motor fluid port smaller than said motor fluid passage and a separate motor fluid port of the same size as said motor fluid passage, each of which ports is adapted to communicate with said motor fluid passage in certain positions of the valve, the interior of said hollow valve piece being in communication with said inlet whenever any of said ports is in operative position, and said valve piece having port means adapted to pass feed fluid to said feed passage while each of said motor fluid ports is in communication with said motor fluid passage.

ALBERT FEUCHT.
